UNITED STATES PATENT OFFICE.

KARL ASSAR THEODOR BERG, OF HOGANAS, SWEDEN.

PNEUMATIC TOOL DRIVEN BY PULSATING AIR.

Application filed December 15, 1921. Serial No. 522,610.

To all whom it may concern:

Be it known that I, KARL ASSAR THEODOR BERG, a citizen of Sweden, residing at Hoganas, Sweden, have invented certain new and useful Improvements in or Relating to Pneumatic Tools Driven by Pulsating Air, of which the following is a specification.

This invention relates to improvements in pneumatic tools driven by pulsating air. When such tools do not work during shorter intervals, they must be constructed in such a way that the pulsating air column is neutralized or suppressed in order to do away with the oscillating suction and pressure periods as completely as possible. Hitherto for this result, when the piston striker has been driven beyond its working position, some holes are uncovered in the cylinder wall, whereby so ample a communication with the atmosphere is obtained that the action on the piston striker almost ceases. In dusty working places, as for instance in stone drilling, stone cutting, foundries etc., such a construction is wearing on the pistons and cylinders of the pneumatic tools, due to the dust drawn in. This drawing in of the impure air is avoided by the present invention, though the piston striker can be thrown out of work when required.

In the accompanying drawing Figs. 1 and 2 show longitudinal sections of a pulsating pneumatic tool of the kind referred to. 1 indicates the working cylinder, 2 the piston striker, 3 the tool guide simultaneously serving as cylinder cover, 4 the working tool, 5 and 6 the air passages and 7 grooves in the walls of the working cylinder. In the drawing four such grooves are shown, though a greater or smaller number also may be used. These grooves reach from the lower edge of the cylinder to slightly beneath the upper edge of the piston striker 2, when the tool 4 is in its proper position, as shown in Fig. 1. In Fig. 2 the tool 4 is shown in its outmost position, in which it is kept by means of a device not shown in the drawing when it is not working. In this case the piston striker 2 travels so far down that the grooves 7 connect the cylinder on both sides of the piston striker. The

difference of pressure is now almost nil and thus the piston striker stands still. By pushing the tool 4 into the position shown in Fig. 1 the piston striker is again brought into play.

This arrangement of the grooves 7 effects that the piston striker can be brought out of work without introducing impure air into the working cylinder.

The inlet 6 in such tools must be provided at a distance from the cylinder bottom in such a way that the space above forms a compression chamber taking up the energy of the piston and preventing the latter from striking the bottom at the same time as the pressure thus produced sends the piston back making it again susceptible of the impulse of the air column through the passages 5 and 6.

Having thus described my invention, what I claim as new and desire to secure by Letters Patent is:—

1. In a pneumatic tool adapted to be driven by a single pulsating air column producing alternating periods of pressure and vacuum, a cylinder having a single inlet only for said air column with the inlet located adjacent the rear end of the cylinder, and a striking piston mounted for reciprocation within said cylinder by said alternating pressure and vacuum, the walls of the cylinder being provided at the forward end with a bypass without direct communication with the pulsating air column, said bypass extending in both directions beyond the striking piston when the latter is at its limit of stroke in non-working position and being continuously closed against the working portion of the cylinder when the piston is operating upon the tool.

2. In a pneumatic tool adapted to be driven by a single pulsating air column producing alternate periods of pressure and vacuum, a cylinder having a single inlet through which said pressure and vacuum operates with respect to the cylinder, and a striking piston mounted for reciprocation within said cylinder and alternately subjected to the pressure and vacuum through said single inlet, said cylinder being formed with means whereby when said piston is

2
in a predetermined position in the cylinder the opposite sides of said piston will be simultaneously subjected to the alternate pressure and vacuum, whereby the piston is held substantially stationary in the cylinder notwithstanding continuous operation of the pulsating air column.

In testimony whereof, I have signed my name to this specification in the presence of two subscribing witnesses.

KARL ASSAR THEODOR BERG.
